UNITED STATES PATENT OFFICE.

ANDREW J. CROPP, OF CHICAGO, ILLINOIS.

MIXING-MACHINE.

949,698

Specification of Letters Patent. Patented Feb. 15, 1910.

Application filed September 17, 1908. Serial No. 453,413.

To all whom it may concern:

Be it known that I, ANDREW J. CROPP, a citizen of the United States, residing at Chicago, in the county of Cook and State of Illinois, have invented certain new and useful Improvements in Mixing-Machines, of which the following is a specification.

My present invention has relation to improvements in a mixing machine, which is more especially intended for mixing ingredients or materials employed for the production of concrete for any of the usual purposes thereof, but may be used for thoroughly mixing ingredients or materials of various kinds for other purposes; and it consists in certain peculiarities of the construction, novel arrangement, and operation of the various parts thereof, as will be herein-after more fully set forth and specifically claimed.

The principal objects of the invention are to provide a mixing machine which shall be simple and inexpensive in construction, strong, durable and efficient in operation.

Numerous other objects and advantages of the invention will be disclosed in the subjoined description and explanation.

Referring to the accompanying drawings which serve to illustrate the invention—Figure 1 is a view in elevation of the discharging end of the mixer, showing the discharging chute mounted near the mixer and extended thereto, and the means for operating said chute; Fig. 2 is a similar view in elevation of the receiving or charging end of the machine; Fig. 3 is a fragmental view in elevation of the central portion of the head of the mixer which is located at its discharging end, showing a portion of the means employed for returning to the interior of the mixer the material which may be spilled from the chute in its act of discharging; Fig. 4 is an enlarged perspective view of a portion of the inner surface of said head, showing one of the inwardly directed tunnels thereon; Fig. 5 is a similar view of the outer surface of a portion of said head, showing one of the inwardly directed deflectors thereon; Fig. 6 is a vertical sectional view taken on line 6—6 of Fig. 1 looking in the direction indicated by the arrows, showing the discharging chute in full lines in about the position it will occupy when in the act of discharging the material and by dotted lines in about the position it will occupy when arranged to deflect the material

inwardly of the mixer; Fig. 7 is a plan sectional view taken on line 7—7 of Fig. 2 looking in the direction indicated by the arrows; Fig. 8 is a somewhat enlarged sectional view of a portion of the feeding or charging end of the mixer or drum, showing one set of the means for guiding the material from the receiving or charging chamber or casing into the mixing receptacle; Fig. 9 is a cross-sectional view of like parts; Fig. 10 is a perspective view of a portion of the head of the mixing receptacle at the charging end thereof, showing one of the guide flanges or deflectors secured thereto; Figs. 11 to 15, inclusive, are detail views of various parts of the machine which will be referred to in the following description.

Like numerals of reference, refer to corresponding parts throughout the different views of the drawings.

The reference numeral 20 designates the mixing receptacle which is in the form of a drum or cylinder and may be made of any suitable size and material, and has circumferentially mounted on its outer surface near each of its ends a band or circular gear 21 which mesh with gears 22 mounted on a driving-shaft 23 which is suitably journaled on a supporting-frame 24 of the ordinary or any preferred construction, and which shaft may be driven by any suitable means. Each of the gear bands or rings 21 is provided with a circular or band-like portion 25 which is adapted to rest on rollers 26 journaled on suitable brackets 26^a mounted on the supporting-frame 24 and in pairs on each side of the mixing drum or receptacle. This drum or receptacle has at its receiving or charging end a centrally apertured head 27 and at its other or discharging end a head 28, which is also provided with an opening 29 at its center for the reception and operation of the discharging chute 30 which extends some distance into the interior of the drum and projects outwardly therefrom through the opening 29, as is clearly shown in Fig. 6 of the drawings, in which view, as well as in Figs. 2 and 7, it will be seen that the front or charging end of the mixing receptacle 20 is provided with a charging chamber or casing 31 which surrounds the front portion or end of the mixing receptacle 20 and projects at its front portion some distance in front of the head 27. As shown the casing 31 is annular when viewed from the front of the machine, but

is substantially U-shaped in cross-section, that is to say, it has front and rear walls 32 and 33, respectively, which are united at their outer edges by a portion 34, thus forming the annular charging casing indicated as a whole by the reference numeral 31, which casing as before stated surrounds the front portion of the mixing receptacle 20 and may be secured thereto in any suitable or well-known manner, but in such a way that the front wall 32 of the casing will be located at a distance in front of the head 27 of the mixing receptacle.

It will be observed by reference to Figs. 2, 6 and 7 that the opening 35 in the wall 32 of the charging casing is much larger than the central opening 27a in the head 27 at the charging end of the mixer, thus permitting the materials to be readily deposited in the casing 31 between the front wall 32 thereof and the head 27 of the mixing receptacle.

The drum or receptacle 20 is provided inwardly of its head 27 with a series of openings 36 which are preferably located at equal distances apart and communicate with the channeled charging casing 31, as will be readily understood by reference to Figs. 2, 6 and 8 of the drawings.

Located diagonally between the wall 32 of the charging casing and the head 27 of the mixing receptacle are a series of guiding plates 37 which recede from the wall 32 in a direction opposite to that of the movement of the mixing receptacle and are joined to the head 27 at or near the front of the openings 36 therein.

Extended from the periphery or outer wall 34 of the casing 31 are a series of inwardly and rearwardly inclined guide plates 38 which are secured by means of a flange 39 on each of said plates to the head 27 and have their rear ends joined to the drum 20 at the rear of the openings 36 therein. Thus it will be seen by reference to Figs. 8, 10 and 11 of the drawings that the flanges 39 on the plates 38 will form one vertical wall for said plates while the wall 33 of the charging casing will form another wall to each of said plates, thus providing inclined passage ways to guide the material from the casing 31 to the interior of the drum or mixing receptacle.

Secured to the inner surface of the receptacle 20 at or near the front end of each of the openings 36 therein is a deflector which consists of a tapered plate 40 which is vertically located with respect to the drum at the inner edge of each of the openings therein, and is secured to the inner surface of the head 27 at a distance therefrom by means of a plate or portion 41, thus forming inwardly and rearwardly directed guide-ways on the inner portion of the mixing receptacle 65 which ways communicate with those formed

by the members 38 and 39 and located in the casing 31 as above described. The members 40 and 41 of said deflectors and the head 27 to which the members 41 may be joined, form tunnel-like chutes leading from the casing 31 into the interior of the mixing receptacle and in the direction opposite its movements.

Diagonally disposed from near the head 27 and partially across the inner surface of the receptacle 20 are a series of wings 42 which may be secured to the receptacle 20 by means of angle brackets 43 or otherwise so as to present their edges inwardly or substantially radially. As shown in Figs. 6 and 7 these wings are located with their ends adjacent to the head 27 forwardly of the members 41 of the guide-ways leading from the casing 31 to the drum and incline rearwardly toward the head 28 of the mixing receptacle where they terminate slightly in front of a series of scoops 44 which may be of any suitable shape, but preferably like that shown in the last-named figures of the drawings. Each of these scoops is preferably made of metal bars having their ends extended forwardly and their intermediate portions bent rearwardly so that, as the material passes from the wings 42 to said scoops, it will be retained thereby and carried upwardly in the rotation of the mixing receptacle. As shown they may be secured at their outer edges to the inner surface of the receptacle 20 by means of angle brackets 45 or otherwise.

Diagonally mounted on each of the diametrically disposed members 41 is a plate 46 which has substantially the same inclination as the wings 42, and are used for the purpose of directing the material which might pass over said wings inwardly from the charging end of the mixing receptacle.

At suitable distances apart and near the central opening 29 therein the head 28 is provided with a series of openings 47 which communicate with a return casing, which is designated as a whole by the reference numeral 48, and is mounted on the outer surface of the head 28 around the central opening therein. This return casing consists of an annular ring 49 which is bolted or otherwise secured to the head 28, and has at its outer edge or portion an inwardly extending flange 50 which is spaced from the head 28 as is clearly shown in Figs. 6 and 7 of the drawings.

Diagonally extended across the return casing 48 from its flange 50 to the head 28 are a series of guide plates 51, which recede from the flange 50 to the rear portion of the openings 47 in the head 28 and may be secured at their ends to said flange and head by bolts or otherwise.

Located on the inner surface of the head 28 and inwardly of the openings 47 therein

are a series of rearwardly enlarged and three-sided box-like chutes 52 which present their tapered portions forwardly or in the direction of the rotation of the mixing receptacle, and have said tapered ends secured forwardly of the openings 47 in the head 28 of said receptacle.

Extended diagonally from the head 28 and rearwardly within the mixing receptacle to about its middle are a series of bars 53 which preferably correspond in number to the wings 42, and have their inner portions secured to said wings by means of brackets 54 or otherwise and their outer ends supported in any suitable manner near or against the head 28 of the mixer.

In Fig. 2 of the drawings I have shown the receptacle 20 as being equipped with four of the wings 42 and with a like number of the bars 53, two of the diametrically located ones of which are supported near their inner ends by means of the brackets 54 at a distance inwardly from the wings 42, while the other two of such bars are supported directly at or near their inner ends on their respective wings.

Mounted on the main or supporting-frame 24 near the discharging end of the receptacle 20 are two spaced apart uprights 55, each of which is provided with an arm 56 which extend through the opening 29 of the head 28 into the mixing receptacle, and have pivotally mounted thereon and therebetween the discharging chute 30 which has each of its ends open. Journaled on the upper portion of the uprights 55 and on the upper portion of a standard 57 at the rear and one side of the mixing receptacle is a horizontal shaft 58 which has on its outer end a crank-handle 59 to turn the same. Mounted on the shaft 58 between the uprights 55 is a crank 60 which is pivotally connected at its lower end to a bail 61 secured to the sides of the chute 30 at a suitable distance from their outer ends.

From the foregoing and by reference to the drawings it will be readily understood and clearly seen that by supplying the ingredients or materials to be mixed to the charging chamber or casing 31, which may be done by dumping the material directly from wheel-barrows over the edge of the wall 32 of said casing or otherwise, it will be caused, in the rotation of the drum or mixing receptacle 20, to pass from the casing 31 through the openings 36 by reason of the guides 37, 38, 40 and 41 into the receptacle 20 or mixer. In the further rotation of the drum or mixer it is apparent that the material will come in contact with the wings 42 which, by reason of their inclination, will guide it toward and into the scoops 44 which will carry it upwardly in batches until they reach a certain point near the top of the receptacle when by rea-

son of the gravity of the material it will fall from the scoops 44 into the chute 30 which may be tilted to the position shown by dotted lines in Fig. 6 by means of the shaft 58 and connections uniting it with the chute. Most of the material falling from the scoops 44 will be deposited in the chute, and as it is inclined inwardly will fall from its inner end to the lower portion of the receptacle 20 where it will be acted upon by the bars 53 and wings 42 in such a manner as to thoroughly mix or intermingle the ingredients, at which time the chute 30 may be tilted to the position shown by continuous lines in Fig. 6, when the same operation as above-described will take place, except that the mixed material will be discharged outwardly from the receptacle. As some of the material may fall over the sides of the chute 30 or pass out of the opening 29 in the head 28 of the receptacle, it is apparent that the return casing 48 will catch the same which, by reason of the guide plates 51, will be caused to pass through the openings 47 and box-like chutes 52 into the interior of the mixing receptacle.

Having thus fully described my invention, what I claim as new, and desire to secure by Letters-Patent, is—

1. In a mixer, in combination, a revoluble drum, having openings in its periphery at the receiving end thereof, means therein to agitate and mix the material, a charging casing mounted around and along the receiving end of the drum and extended substantially the same length as the openings in the periphery of the drum and extending beyond the periphery of said drum and having an opening in its end.

2. In a mixer, in combination, a revoluble drum, having openings in its periphery at the receiving end thereof, means therein to agitate and mix the material, a charging casing mounted around and along the receiving end of the drum and extended substantially the same length as the openings in the periphery of the drum and extending beyond the periphery of said drum and having an opening in its end, and means to guide the material inwardly from the casing to the drum, and having its front wall extended forwardly and beyond the drum, and means to direct the material inwardly from the casing.

3. In a mixer, in combination, a drum, having openings in its periphery at the receiving end thereof, means therein to agitate and mix the material, a continuous series of circularly arranged charging pockets located at one end of the drum, outside of its cylindrical wall and closed at their outer ends, the open inlets of the pockets being turned toward the axis of the drum, a circular head having its periphery contacting with the tops of the pocket walls,

and means to introduce the material to the inlets of the pockets outside of said head.

4. In a mixer, in combination, a revoluble drum, having openings in its periphery at 5 the receiving end thereof, means therein to agitate and mix the material, a continuous series of circularly arranged recharging pockets located at the discharging end and around the discharge opening, the open

inlets of the pockets being turned toward 10 the axis of the drum, and means to guide the material to the inlets of the pockets outside of the discharge opening.

ANDREW J. CROPP.
